CLASP FASTENER

Abraham Novick, Flushing, N. Y., assignor to F. L. Smith Machine Co., Inc., New York, N. Y., a corporation of New York

Application November 5, 1940, Serial No. 364,367

5 Claims. (Cl. 24—153)

This invention relates to clasp fasteners for envelopes.

It has been the common practice in the past to make clasp fasteners of the arm and leg type. Such a fastener is a thin sheet metal member having a central body portion from which attaching legs extend in opposite directions. Each attaching leg is commonly formed with a central opening bordered by attaching prongs, the prongs being adapted to be driven through the back of an envelope and clinched to secure the fastener firmly in place thereto. The fastener also includes bendable arms which extend in opposite directions from the central body portion, the arms being disposed substantially at right angles to the legs. When the fastener is applied to the back of an envelope, the arms initially lie flat against the envelope. They are adapted, however, to be bent upward in parallelism, to be passed through an opening formed in the closure flap of the envelope and then folded outward again substantially to their original positions to hold the closure flap closed.

Fasteners of the kind referred to are invariably stamped from thin malleable sheet metal. During the manufacture of such fasteners the arms of a substantial number become bent out of alignment with the body portion and with each other so that when a quantity of such fasteners are placed in the hopper of an affixing machine which attaches the fasteners to envelopes, the bent fasteners have a tendency to accumulate in the hopper and materially retard the operation of the machine and decrease its productivity. It is an object of the present invention to prevent the bending of the legs of the fasteners by means of a reinforcing rib formed on the fasteners at the time of their manufacture. The formation of such a rib on the fasteners obviates the tendency of the fastener arms to become bent and thus prevents the accumulation of bent fasteners in the hopper of the attaching machine. It has further been found that the provision of such a reinforcing rib on the fasteners, reduces the friction between them and certain parts of the affixing machine and facilitates the free travel of the fasteners from the hopper to the tool which affixes them to the envelopes. It is found that the use of such a reinforced fastener substantially increases the output of an affixing machine.

It has also been found when plating in a plating basket, fasteners of the usual type in which the main body portion and arms of the fastener are flat, that a pair of adjacent fasteners often

lie back to back with their flat surfaces in contact, so that the plating solution cannot reach such surfaces. The desired coating is therefore not applied to such surfaces. It is a further object of the present invention to overcome this drawback by providing a rib on the arms of the fasteners which will keep their surfaces separated during the plating operation so that the plating solution can readily reach all parts of each fastener, resulting in a more uniform coating of plating material and assuring that the entire surface of each fastener will receive a plated coating.

Another object of the invention is to provide a reinforcing rib which extends between the bendable arms of a paper fastener by pressing, as by means of a die, such a fastener so as to form a groove in one face thereof with the concomitant formation of a reinforcing ridge or protuberance on the opposite face thereof.

Other objects and advantages of the invention will hereinafter appear.

In the drawing forming part of this specification and illustrating a paper fastener embodying the invention:

Fig. 1 is a top plan view of a fastener embodying the invention;

Fig. 2 is a front view of the fastener shown in Fig. 1;

Fig. 3 is a sectional view taken upon the line 3—3 of Fig. 1 looking in the direction of the arrows; and,

Fig. 4 is a top plan view of a fastener embodying a modified form of the invention.

The fastener of Fig. 1 is composed of thin sheet metal and comprises a central body portion 1, a pair of legs 2 which extend in opposite directions from the central body portion, and a pair of arms 3 which also extend in opposite directions from the central body portion and substantially at right angles to the direction in which the legs extend. The legs 2 are formed with central openings 4, each bordered by a set of upstanding, triangular attaching prongs 5. The central portion of the fastener is pressed by means of a suitable die to deform the metal thereof and form a long projecting ridge 6 which extends along the longitudinal axis of the arms 3 and serves as a reinforcing rib to stiffen the arms and prevent them from bending during the process of manufacture or while the fasteners are being packed or transported to the machine which affixes them to the envelopes.

The ridge 6 is preferably pressed in the fasteners before they are stamped out of a sheet metal

strip in a machine such as that disclosed in Patent No. 2,268,080 issued on December 30, 1941 in my name. In said patent a machine for making clasp fasteners from a strip of sheet metal is disclosed in which a first station is provided with a set of four punches arranged to punch upturned attaching prongs for four clasp fasteners in the metal strip at spaced apart regions thereof. The strip is then fed to a second station at which the four fasteners including their attached prongs are punched and separated from the strip. According to the present invention, an extra set of four forming dies may be provided in such machine between the first and second stations, these dies being constructed to depress four reinforcing ridges in the strip, one for each of the four fasteners to be struck therefrom. Or, alternatively, the ridge 6 may be pressed in the fasteners by means of a forming die in a separate machine to which the otherwise finished fasteners are supplied.

In the preferred form of the invention shown in Fig. 4, the ridge 6' is not uniform in width throughout its length but is made somewhat narrower at the central body portion of the fastener as indicated at 7 to facilitate the bending of the arms 3 at the regions where they join the body portion of the fastener. The central portion 7 of the ridge 6' may also be of lesser depth than the remainder of the ridge to further facilitate such bending of the arms.

I have described what I believe to be the best embodiments of my invention. I do not wish, however, to be confined to the embodiments shown, but what I desire to cover by Letters Patent is set forth in the appended claims.

I claim:

1. A thin sheet metal arm and leg fastener for envelopes comprising a central body portion, a pair of attaching legs extending in opposite directions from the central body portion, each of said legs being provided with a plurality of attaching prongs, a pair of bendable arms also extending in opposite directions from the central body portion and at substantially right angles to the legs, the central part of said arms and body portion being bent downwardly to form an arm reinforcing ridge adapted to obviate undesired bending of the arms out of alignment with the central body portion.

2. A thin sheet metal arm and leg fastener for envelopes comprising a central body portion, a pair of attaching legs extending in opposite directions from the central body portion, said legs being provided with attaching prongs, a pair of bendable arms also extending in opposite directions from the central body portion and at substantially right angles to the legs, the central part of said arms and body portion being bent downwardly to form an arm reinforcing ridge, the width of said ridge being less throughout the central body portion than throughout the portions thereof extending along the arms.

3. A thin, malleable, sheet metal clasp fastener

for envelopes adapted for hopper feeding and comprising a central body portion, pronged legs extending laterally in opposite directions from the body portion, bendable arms extending lengthwise in opposite directions from the body portion, said arms having zones of easiest bending at the junctions of the arms with the body portion, and a longitudinally extending reinforcing rib running substantially from an outer end of one arm through the body substantially to the outer end of the opposite arm, said reinforcing rib having portions which extend through the zones of easiest bending but being of no less rigidity in other portions of the arms than in said zones, whereby the zones of easiest bending are clearly defined adjacent the body but even these zones are provided with a predetermined, limited measure of reinforcement to oppose accidental bending.

4. A thin, malleable, sheet metal clasp fastener for envelopes adapted for tumbling, plating and hopper feeding, and comprising a central body portion, attaching legs extending laterally in opposite directions from the body portion, said legs being formed with central openings bordered by downwardly extending attaching prongs, arms extending lengthwise in opposite directions from the central body portion and of too great width to enter said openings, said arms having zones of easiest bending at the junctions of the arms with the body portion, and an upwardly projecting, longitudinally extending reinforcing rib running substantially from an outer end of one arm through the body substantially to the outer end of the opposite arm, said rib serving to provide reinforcement against accidental bending in the zones of easiest bending at the junctions of the arms with the body, but being of no less cross-section and rigidity in the other portions of the arms than in said zones of junction and serving therefore to reinforce the arms and body against bending so that the zones of junction will be definitely zones of easiest bending notwithstanding the reinforcement of said zones against bending.

5. A thin, malleable, sheet metal clasp fastener for envelopes adapted for hopper feeding and comprising a central body portion, pronged legs extending laterally in opposite directions from the body portion, a bendable arm extending from the body portion substantially at right angles to the legs, said arm having a zone of easiest bending at the junction of the arm with the body portion, and a longitudinally extending reinforcing rib running substantially from an outer end of said arm into the body, said reinforcing rib having a portion which extends through the zone of easiest bending but being of no less rigidity in other portions of the arm than in said zone, whereby the zone of easiest bend is clearly defined adjacent the body, but even this zone is provided with a predetermined, limited measure of reinforcement to oppose accidental bending.

ABRAHAM NOVICK.
